UNITED STATES PATENT OFFICE.

BENJAMIN BERNARD DEITEL, OF BROOKLYN, NEW YORK.

NOVELTY CASE.

Application filed December 13, 1928. Serial No. 325,701.

My invention relates to containers, particularly, to the class of containers used as novelties, such as, for instance, vanity cases.

The object of the invention is to produce a container of this character which is simple in construction, requiring but few parts in the making, thus eliminating a great many of the tools and dies now used in the manufacture of such articles, and, at the same time, combine ruggedness with an artistic and pleasing appearance.

The container, described below, similarly to those disclosed in my U. S. Patent No. 1,694,702, and my application for patent Serial No. 323,603, comprises a lid or cover which is made up of a plate and a framework, joined together, the framework being arranged in each particular instance so as to meet the especial requirements of the article. As an illustration, I have shown its application to a vanity case, the framework of the lid, accordingly, being so made up as to comprise a mirror, but, obviously, this framework would be otherwise constructed if the article were intended for some other purpose. For example, when the container is intended for a pocket savings bank, the framework joined to the lid may comprise a locking mechanism of the character well known in such articles. Neither this particular, nor other illustration, besides the vanity case, is shown in the drawings because this feature of the device is not new and no claim therefor is made here or in the above mentioned patent and patent application.

The container is made to simulate a book. In the patent and patent application referred to above, the facing, which represents the binding of the book, is secured to the main body of the container by means of separate channel members. In the present invention, the securing channels are formed by bending the flanges or edges of the framework of the lid, as will be seen from the detailed description which follows.

In the drawing, Figure 1 is a perspective view of a container embodying my invention. Figure 2 is a plan view of the same container when open, the left hand part (which is the lid) being shown in its finished form, and the right hand part with the flanges of the container frame before these are bent upon themselves to form channels. Figures 3 and 4 are cross sections along the line 3—3 of Figure 1, differing from one another in that, in Figure 3, the cover plate of the lid

is hinged to the walls of the container frame, while, in Figure 4, the hinge is between the latter and the framework of the lid. Figure 5 is a detail of a corner of the container.

Referring to the figures in detail, 1 is an open frame made preferably of sheet metal and constituting the four walls of a container designed to simulate a book, the front and the two end walls representing the front and the end leaf edges of the book. At its nether periphery, the container frame 1 is formed into outwardly projecting flanges 2 on three sides, namely, at the front and at the two ends of the "book". To the container frame 1 is attached, in the manner described below, a cover plate 3 constituting the bottom of the container. The lid comprises a top cover plate 3' and a framework 2', which, in this particular illustration, is a flat open frame formed of a rectangular piece of sheet metal having a hole cut out of it so as to leave peripheral margins somewhat wider than the flanges 2 (before these are bent upon themselves). The plate 3' and framework 2' are joined to one another as will be explained later. I may attach the lid to the container frame 1 either by hinging the cover plate 3' thereto, as in Figure 3, or by connecting the framework 2' with the container frame 1 in a similar fashion, as in Figure 4. A facing 4, simulating the binding of a book, covers the two plates 3 and 3' and the back wall of the container frame 1. The bottom plate 3 has tongues 17 which pass through slots 18 in the back wall of frame 1 and are bent over flush with this wall. This secures the bottom plate 3 to the container frame 1. The plate 3 is further secured thereto, together with the facing 4, by bending the flanges 2 upon themselves to form channels 5 and clamping the edges of the "book" tightly together. At the corners, as at 5', Figure 2, the flanges 2 are cut in the manner shown so that, after being bent into position, the cut ends come together flush, as seen in Figure 1. I may, also, provide a corner piece 19, to cover up the seam, as shown in Fig. 5, in which case the flanges 2 would be cut straight a little before reaching the corner, before being bent into the channels 5, as is indicated in dotted lines in Figure 5.

The facing 4 and the framework 2' are similarly secured to the top cover plate 3' by bending the edges of the framework 2' upon themselves to form channels the back and front of which are pressed together as in

the case of the bottom part of the container.

The walls of the container frame 1 may be provided with additional but inwardly projecting flanges 7. The box space formed by frame 1 and the bottom plate 3 may be divided into compartments, as shown, each comprising a shallow pan, such as 9 and 10, one for powder and the other for rouge, separated and, at the same time, held in place by a cross piece 11. Pads containing rouge and face powder may be provided, as indicated in the drawing by dotted lines and the numerals 12, 13. Any form of suitable closure may be employed. As an illustration, the ordinary snap catch 8 is shown, secured to the framework 2'. The inward edges of the framework 2' are formed into bezels 14, for which purpose the margin of this framework has been left wide enough, as stated above. A mirror 15 is set within the bezels 14 and rests against the top cover 3'. The bezels 14 are so spaced that when the container is closed they can pass the inwardly projecting flanges 7 of the container frame 1.

25 The facing 4 is turned inwardly at 16 in the manner well known in the art of book binding.

The container need not be rectangular in shape, this shape being illustrated here only 30 because of the simulation of a book, nor is it necessary that the top and bottom be identical in shape or size.

I claim:

1. A container comprising an open frame 35 constituting the walls thereof, outwardly projecting flanges on said frame at one of its peripheries bent upon themselves along the edges to form channels, a bottom plate resting against said flanges and extending into said channels, a cover hinged to said frame comprising a framework having edges bent upon themselves to form channels and a top plate resting against said framework and extending into said last mentioned channels, and a 40 facing extending over said top and bottom plates and into said channels and covering the hinged portion of said container frame, said channels clamping said facing and said plates together.

50 2. A container comprising an open frame constituting the walls thereof, outwardly projecting flanges on all but one of said walls bent upon themselves along the edges to form channels, slots in the remaining one of said walls, a bottom plate resting against said flanges and extending into said channels, tongues on said bottom plate passing through said slots and bent flush with said slotted wall, a cover hinged to said slotted wall comprising a flat frame adapted to carry a mirror and having its front and end edges bent upon themselves to form channels and a top plate resting 55 against said flat frame and extending into said last mentioned channels, and a facing simulating the binding of a book extending over said top and bottom plates and into said channels and over said slotted wall, said channels clamping said plates and facing together.

tioned channels, and a facing extending over 65 said top and bottom plates and into said channels and over said slotted wall, said channels clamping said plates and facing together.

3. A container comprising an open frame 70 constituting the walls thereof, outwardly projecting flanges on all but one of said walls bent upon themselves along the edges to form channels, a bottom plate resting against said flanges and extending into said channels, a framework hinged to the remaining one of 75 said walls and having its edges bent upon themselves to form channels on all sides except the side of said hinged wall, a top plate resting against said framework and extending into said last mentioned channels, and a 80 facing extending over said top and bottom plates and into said channels and over said hinged wall, said channels clamping said plates and said facing together.

4. A container simulating a book and comprising an open frame constituting the walls thereof, the front and the two end walls representing the front and the end leaf edges of said book, outwardly projecting front and end flanges on said frame along one of its 90 peripheries bent upon themselves along the edges to form channels, a bottom plate resting against said flanges and extending into said channels, a cover hinged to the back wall of said frame and comprising a framework 95 having its front and end edges bent upon themselves to form channels and a top plate resting against said framework and extending into said last mentioned channels, and a facing simulating the binding of a book extending over said top and bottom plates and into said channels and over said back wall, said channels clamping said plates and facing together.

5. A vanity case simulating a book and 105 comprising an open frame constituting the walls thereof, the front and the two end walls representing the front and the end leaf edges of said book, outwardly projecting front and end flanges on said frame along one of its peripheries bent upon themselves to form channels along the edges, slots in the back wall of said case, a bottom plate resting against said flanges and extending into said channels, tongues on said plate passing through said 110 slots and bent flush with said back wall, a cover hinged to said back wall comprising a flat frame adapted to carry a mirror and having its front and end edges bent upon themselves to form channels and a top plate resting 115 against said flat frame and extending into said last mentioned channels, and a facing simulating the binding of a book extending over said top and bottom plates and into said channels and over said back wall, said channels clamping said plates and facing together.
